US0D1087072S

(12) **United States Design Patent** (10) **Patent No.:** **US D1,087,072 S**
(45) **Date of Patent:** **** Aug. 5, 2025**

(54) **EARBUD COVERS**

(71) Applicant: **Class and Culture LLC**, Las Vegas, NV (US)

(72) Inventor: **Ronald Mok**, Las Vegas, NV (US)

(73) Assignee: **Class and Culture LLC**, Las Vegas, NV (US)

(**) Term: **15 Years**

(21) Appl. No.: **29/891,291**

(22) Filed: **May 3, 2023**

(51) LOC (15) Cl. **14-01**

(52) U.S. Cl.

USPC **D14/223**

(58) **Field of Classification Search**

USPC D14/223, 205, 217, 192, 250; D3/201; D24/174; D6/582, 591, 611; D12/203; 128/864-866, 868; 181/129-130, 135; 381/329, 318, 322, 324; 428/116, 172; 296/97.23; 15/215

Primary Examiner — Paula Allen Greene

(74) Attorney, Agent, or Firm — Polsinelli LLP

(57) **CLAIM**

The ornamental design for an earbud covers as shown and described.

DESCRIPTION

FIG. 1 is a perspective view of earbud covers showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 6 Drawing Sheets
